UNITED STATES PATENT OFFICE.

OSCAR S. WINESBURG AND IRVIN G. PALMER, OF ELKHART, INDIANA.

AUTOMATIC STICK-FEEDING MACHINE.

1,300,540.

Specification of Letters Patent. Patented Apr. 15, 1919.

Application filed August 6, 1917. Serial No. 184,785.

To all whom it may concern:

Be it known that we, OSCAR S. WINESBURG and IRVIN G. PALMER, citizens of the United States, and residents of the city of 5 Elkhart, Elkhart county, Indiana, have invented certain new and useful Improvements in Automatic Stick-Feeding Machines, of which the following is a specification.

10 Our invention relates to machinery for drying freshly coated paper, or sized or printed paper, or other fabric, and more especially to the mechanism for feeding the paper carrying sticks, or laths, which support the looped paper as it travels through the drying room.

An object of our invention is the provision of improved devices for automatically feeding or supplying the paper carrying 20 laths to the paper loop forming mechanism of the paper drying machinery, the automatic mechanism of our invention being particularly adaptable to that type of paper drying machine having the so called "re- 25 turn" conveyer lines in which the dried paper and lath are discharged or delivered adjacent the location where the freshly treated, or coated, paper is formed into loops immediately prior to its entry to the drying 30 room.

While our invention is especially applicable to the flat paper carrying lath, or stick, and such a lath is shown and described herein, nevertheless our invention may be used 35 in those machines in which the flat lath is not used. Other objects of our invention will be mentioned and described hereinafter.

The accompanying drawings clearly illustrate the preferred embodiment of our invention which may be changed within reasonable limits without departing from the spirit thereof.

On the drawings, Figure 1 is a plan view of our invention applied to a paper drying 45 machine, the latter being shown in fragment only; Fig. 2 is a side elevation of our invention applied to the drier machine; Fig. 3 is a section taken on the line 3—3 of Fig. 1 in which details of the magazine unit C and 50 unit D are shown; Fig. 4 is a perspective view of a special link used in the lath lowering chains of the magazine unit C; Fig. 5 is a section taken on the line 5—5 of Fig. 7 to disclose one of the lath conveyer chains 55 of unit G; Fig. 6 is a view in elevation taken approximately on the line 7—7 of Fig. 1 showing details of the transfer and receiver

box units E and F, respectively; Fig. 7 shows a section taken on the line 7—7 of Fig. 1; Fig. 8 shows details of the unit D 60 which includes the lath supply chain to the lath transfer unit E, as well as other details coöperating therewith and is a section taken on the line 8—8 of Fig. 1; and Fig. 9 shows a section taken on the line 9—9 of Fig. 3 disclosing fragments of each of the units C and D. 65

Similar numerals of reference indicate similar members and parts of members throughout the several views on the drawings.

For convenience in differentiating the various parts and units of our invention and the drier machine the letter A indicates the paper loop forming unit; the letter B, the 75 loop carrying unit; the letter C, the lath magazine unit; the letter D, the lath supply unit which connects unit C with unit E, the latter being the lath transfer unit; the letter F, the lath receiver and supply unit 80 for unit A; and the letter H, the driving unit or mechanism.

In the operation of our invention the inclined loop forming chains 1, 1 carrying lugs 2, 2, engage a flat lath 3 and carry it up 85 the incline against the sagging paper 4, whereby a paper loop is formed and subsequently deposited upon the chains 5, 5, of the loop carrying unit B by which the successive paper loops are carried into and 90 through a drying room (not shown) and ultimately deposited upon the lath discharge chains 7, 7 of unit B by which the laths are conveyed to the magazine unit C, and from which the dried paper 4 passes over the rollers 10 and 11 out of the machine for suitable 95 disposition.

Thereafter, the laths 3 which accumulate in the magazine unit C are individually conveyed by the unit D to unit E; thence 100 through the units F and G and again deposited by the latter mechanism upon the chains 1, 1 of the paper loop forming unit A. The chains 1, 1 are suitably supported and guided by the inclined members 6, 6, and 105 the lath carrier chains 7, 7 are mounted upon the sprocket wheels 8, 8 which are carried by a shaft 12 suitably journaled in the end of the frame member 9.

Unit C—Lath magazine.

110

The numeral 13 indicates the magazine frame wall on the opposite ends of which are disposed the end upright members 14, 14.

The numeral 15 indicates a lath tilting block rigidly fastened to the upper end of one of the members 14, extending transversely thereof and positioned adjacent the sprocket 5 wheel 8 within the magazine unit. The numerals 16, 16 indicate apertures formed in the magazine wall 13 to enable the operation of the chains 29, 29 of the unit D, as hereinafter described. The numerals 17, 17 indicate a pair of upright and spaced lath lowering chains disposed in front of the magazine wall 13, the upper ends of which, said chains being endless, are carried by the sprockets 22, 22 mounted upon the 15 idler shaft 18 which is suitably journaled in the bearing standards 20 and 21, and driven at their lower ends by the sprockets 23, 23 mounted upon the shaft 19 suitably journaled in said bearing standards. The numerals 24, 24 indicate a plurality of special carrier links inserted in each chain 17 and provided with a hinge pin 25 upon which a lath saddle 26 is pivotally mounted, said saddle being adapted to fold upwardly 25 against the chain 17 when its under surface contacts with a lath 3 which may be reposing within the lath magazine to permit the passage thereof. While we show only four of said lath saddles 26 in Fig. 3 on each 30 chain of said figure, any suitable number of the saddles may be used, a multiplicity being preferable to a paucity thereof, said saddles being adapted to receive and support lath when discharged from the chains 7, 7 35 of the unit B and lower it to the top of the lath pile already accumulated within the magazine unit C. When a lath 3 is so discharged from the chains 7, 7 one end thereof is always arrested and temporarily carried 40 by the block 15, causing the lath to partially rotate, whereby it ultimately lies flat on a pair of the chain saddles 26 by which it is lowered in a flat position, which position is very essential to effect accuracy and regularity of the subsequent movements of said lath. 45 A pair of upright chain partitions 27, 27 may be used between each chain 17 for maintaining its proper relation with the lath magazine. The numerals 28, 28 indicate a 50 pair of magazine floor members arranged within the members 14, 14 and extending transversely of the magazine, being adapted to carry the lath accumulation within the magazine. See Fig. 9.

55

Unit D.

The numerals 29, 29 indicate a pair of endless lath transfer chains coöperating with unit C for the transfer of the laths 60 therefrom to unit E, each of said chains having a lug 30 adapted to simultaneously engage the bottom lath in the magazine and draw it therefrom for disposition in unit E. See Fig. 8.

65 Numerals 31, 31 indicate driver sprockets

upon which chains 29, 29 are mounted at one end thereof, said sprockets being operatively mounted upon the driving shaft 32 which is actuated as hereinafter described. Numerals 33, 33 indicate idler or carrying 70 sprockets supporting the opposite ends of the chains 29, 29, said sprockets being mounted upon a shaft 34 suitably journaled in the machine frame.

Unit E.

75

The numeral 35 indicates a lath transfer box positioned adjacent the forward end, being the discharge end, of the chains 29, 29 and somewhat lower than said chains to 80 facilitate the discharge of the laths 3 from the chains 29 into said box and the retention thereof by said transfer box. The box 35 may be open at both ends thereof and is provided with a pair of endless spaced 85 chains 36, 36 which travel longitudinally of the box and within the grooves 37, 37 formed in the floor of said box, said grooves being adapted to position the chain links below the floor surface of said box. At one end of 90 the chains 36 they are supported and driven by the sprockets 38, 38 operatively mounted upon a driver shaft 39, the opposite chain ends being carried by a pair of sprockets 40, 40 mounted upon a carrier shaft 41. Beneath the box 35 the chains 36 are engaged by the idler sprockets 42, 42 mounted upon the shaft 43 which is journaled in the brackets 44, 44. See Figs. 6 and 7.

Numerals 45, 45 indicate two curved or 100 semicircular lugs carried by the chains 36, 36 and adapted to move a lath 3 from the box 35 into unit F, each of said lugs extending substantially across the box and having its ends mounted upon the spaced chains 36, 105 36. Each lug 45 is of curved formation to facilitate the disengagement with the rear end of the lath and to prevent the tilting of the lath at the moment of lug disengagement therewith.

Units F and G.

110

The numeral 46 indicates a lath receiving and supply box which is open at the lath receiving end adjacent unit E and closed at 115 its opposite end, being adapted to receive the laths delivered from box 35 by the chains 36, 36. The numerals 47, 47 indicate a pair of endless chains operating transversely of the box member 46 and in the grooves 48, 120 48 formed in the floor of the box, and adapted to supply the laths 3 to the paper loop forming chains 1, 1 of unit A hereinbefore described. The discharge end of the chains 47 is carried by the driver sprockets 49, 49, 125 which are rigidly mounted upon a driving shaft 50, which shaft is driven by means hereinafter described. The numerals 51, 51 indicate a pair of carrier sprockets upon which the chains 47, 47 are mounted and 130

which are supported by the shaft 52 suitably journaled in the machine frame.

Numerals 53, 53 indicate a pair of lugs, one on each chain 47, and adapted to engage 5 a lath for effecting movement thereof from box 46 to and delivery upon chains 1, 1. The numeral 54 indicates a swinging door forming the front wall of the box 46 and hinged at 55, 55 upon the rod 56 and adapted 10 to be swung open by the lath 3 when the latter is drawn forward by the lugs 53 to permit the lath passage, and adapted also, when in a normal closed position, to guide the incoming lath when the latter is being projected 15 from box 35 into box 46 and for properly positioning the lath within the box 46, whereby subsequent accurate engagement of said lath by the lugs 53 is effected.

20 *Unit H—Driving mechanism.*

Numerals 57 indicates an electric motor adapted to drive the various units of our invention and from which the driving chain 58 extends to an initial driving sprocket 59 25 which is rigidly mounted upon the main driving shaft 60. Numeral 61 indicates a driver sprocket rigidly mounted upon the shaft 60 and connected with shaft 50 by a sprocket 62, mounted upon the latter, and 30 the sprocket chain 63.

The shaft 50 carries a sprocket 64 adjacent one end thereof which is adapted to drive the shaft 19 of unit C through the receiving sprocket 65, mounted upon the latter shaft, and the chain 66 connecting said sprockets. The counter shaft 67 is driven by the shaft 60 through a pair of bevel gears 68, 68, and the shaft 39 is driven by said counter shaft through the driver sprocket 40 69, mounted on said counter shaft, the chain 70 and the sprocket 71 mounted on the driven shaft 39.

For driving the shaft 32 of unit D a second counter shaft 72 is provided and driven 45 from the first counter shaft 67 through the bevel gears 73, 73, the bevel gears 74, 74 effecting coöperation between the shafts 72 and 32 whereby the latter is driven. Generally, we have found that five pairs of the 50 loop forming lugs 2, 2 suitably spaced on the chains 1, 1 are sufficient therefor when properly timed for registry with the one pair of lath actuating lugs 53 carried by the chains 47, 47 of unit G.

55 We claim:

1. In combination with paper drying machinery and the loop forming mechanism thereof, the following elements in combination: a lath magazine, including means for 60 receiving and lowering the lath into said magazine; conveyer members for extracting the lath from said magazine and supplying a lath transfer unit; a lath transfer unit, including curved lath actuation members; a 65 lath receiver unit; and a lath supply unit

adapted to supply lath to the loop forming devices of the drying machinery.

2. In combination with paper drying machinery and the loop forming mechanism thereof, the following elements in combination; a lath magazine, including means for 70 tilting the lath and means for lowering the lath into the magazine; conveyer members for extracting the lath from said magazine and supplying a lath transfer unit; a lath transfer unit; a lath receiver unit; and a lath supply unit adapted to supply lath to the loop forming mechanism of the drying machinery.

3. In combination with paper drying machinery and the loop forming mechanism thereof, the following elements in combination: an upright lath magazine; conveyer members for extracting the lath from said magazine and supplying a lath transfer 80 unit; a lath transfer unit arranged transversely of said conveyer members; a lath receiver unit coöperating with said transfer unit and provided with means for guiding the lath as it enters therein; and a lath supply unit adapted to supply lath to the loop forming mechanism of the drying machinery.

4. In combination with paper drying machinery and the loop forming mechanism 95 thereof, the following elements in combination: a lath magazine; conveyer members for extracting the lath from said magazine and supplying a lath transfer unit; a lath transfer unit; a lath receiver unit coöperating 100 with said transfer unit and provided with a swinging member for guiding the lath as it enters therein; and a lath supply unit operating transversely of said receiver unit and adapted to supply lath to the loop forming mechanism of the drying machinery.

5. In a device of the character described and in combination with a lath magazine and the means for delivering lath thereto, a plurality of endless lath lowering members, 110 said lowering members being provided with saddles each adapted to support a lath while it is being lowered into said magazine; and means for actuating said lath lowering members.

6. In a device of the character described and in combination with a lath magazine and the means for delivering lath thereto, a plurality of endless lath lowering members, said lowering members being provided 120 with foldable saddles each adapted to support a lath while it is being lowered into said magazine; and means for actuating said lath lowering members.

7. In a device of the character described 125 and in combination with a lath magazine and the means for delivering lath thereto, an endless lath lowering device, said lowering device being provided with a plurality of yieldable saddles each adapted to support 130

- a lath while it is being lowered into said magazine; and means for actuating said lath lowering device.
8. In a device of the character described and in combination with a lath magazine and the means for delivering lath thereto, a lath tilting member arranged upon one end of the lath magazine and adapted to temporarily arrest one end of the lath as it is delivered for disposition in the magazine, whereby the lath is ultimately delivered in a flat position in the magazine.
9. In a device of the character described, an upright lath magazine; a plurality of endless upright traveling lath lowering members disposed adjacent the magazine, said lowering members having downwardly movable sections coöoperating with the magazine interior; means carried by the lowering members for supporting the lath; and means for tilting and temporarily arresting one end of a lath as it is delivered for disposition to the magazine.
10. In a device of the character described, a lath transfer receptacle; an endless movable lath actuation device longitudinally arranged within said lath receptacle; a lug carried by said actuation device and movable therewith; said lug being of substantially curved formation; and means for actuating said endless device longitudinally of the transfer receptacle.
11. In a device of the character described, a lath transfer box; a plurality of endless movable conveyer members longitudinally arranged within said box; a curved lug carried by said conveyer members and movable therewith; and means for actuating the conveyer members longitudinally of the transfer box.
12. In a device of the character described, a lath transfer box the floor whereof is provided with a plurality of substantially parallel conveyer chain grooves; a plurality of endless conveyer chains movably disposed within said chain grooves; a substantially curved lug carried by said chains and movable therewith; and means for actuating the conveyer chains and thereby said lug.
- 50 13. In a device of the character described, a lath supply receptacle the floor whereof is provided with a transverse groove; an endless conveyer member arranged within said floor groove and movable therein; a lath actuation lug carried by the conveyer member; and means for actuating said conveyer member.
14. In a device of the character described, a lath supply receptacle; an endless conveyer member arranged transversely of the supply receptacle and provided with a lath actuation lug; a swinging member disposed adjacent the supply receptacle and composing one wall thereof and adapted to be swung open under conveyer actuation; and means for actuating said conveyer member.
15. In a device of the character described, a lath supply box; an endless conveyer member arranged transversely of the supply box and provided with a lath actuation lug; a movable member disposed adjacent the supply box and composing one wall thereof and adapted to be moved aside under conveyer actuation to permit the passage of a lath; and means for actuating said conveyer member.
16. In a device of the character described, a lath supply box the floor whereof is provided with a pair of spaced transverse grooves; a pair of endless conveyer chains operatively arranged in said supply box floor grooves; each chain being provided with a lug; a swinging member disposed adjacent the supply box and constituting substantially one side wall thereof and adapted to be swung open under conveyer actuation; and means for actuating said conveyer members in unison.
17. In combination with paper drying machinery and the loop forming mechanism thereof, the following coöoperative elements in combination: a lath magazine; conveyer members for extracting the lath from said magazine and supplying a lath transfer unit; a lath transfer unit; a lath receiver unit; and a lath supply unit in coöperation with said lath receiver unit and adapted to supply lath to the loop forming devices of the drying machinery.

In testimony whereof we have hereunto affixed our signatures this third day of August, 1917.

OSCAR S. WINESBURG.
IRVIN G. PALMER.
